HAND COUNTER

Earl Rudduck, 5616 E. Argyle Drive,
Phoenix, Ariz. 85018

Filed Feb. 18, 1971, Ser. No. 116,732

Term of patent 14 years

Int. Cl. D18—01

U.S. Cl. D64—11

FIG. 1 is a front and right side perspective view of a hand counter showing my new design;

FIG. 2 is a right side elevational view thereof;

FIG. 3 is a top plan view thereof;

FIG. 4 is a front elevational view thereof;

FIG. 5 is a rear elevational view thereof.

I claim:

The ornamental design for a hand counter, as shown.
